UNITED STATES PATENT OFFICE.

ALVAH D. HADSEL, OF DORRANCETON, PENNSYLVANIA.

CONCRETE-MIXER.

1,016,920.

Specification of Letters Patent.

Patented Feb. 6, 1912.

Application filed November 19, 1910. Serial No. 593,219.

To all whom it may concern:

Be it known that I, ALVAH D. HADSEL, a citizen of the United States, residing at Dorranceton, in the county of Luzerne and State 5 of Pennsylvania, have invented a new and useful Concrete-Mixer, of which the following is a specification.

This invention relates to machines for mixing batches of plastic materials, such as concrete, and comprises certain specific novel features of construction as are hereinafter fully described and claimed, and illustrated in the accompanying drawings, in which—

Figure 1 is a side elevation of the invention; Fig. 2 is a transverse central vertical section of the same; Fig. 3 is a view of the delivery end of the drum and associated devices; Fig. 4 is a fragmentary plan view of the discharge mechanism, and Fig. 5 is a 20 detail perspective view of one of the mixing flights.

Throughout the following description and on the several figures of the drawings similar parts are referred to by like reference 25 characters.

Referring particularly to the drawings, which are to be understood as covering a preferred embodiment of the invention without restricting the invention unnecessarily to 30 the form thereof illustrated, the numeral 10 indicates generally a mixing drum, which is preferably cylindrical and adapted to be rotated continuously in one direction around a fixed axis. The drum is provided with a 35 gear member consisting of a hub 11, spokes 12, and a rim 13. The rim is provided with gear teeth 13^a and a pair of flanges 13^b which extend therefrom in opposite directions toward the ends of the drum. The 40 curved portion of the cylindrical drum consists essentially of two shells or sections 10^a and 10^b, the adjacent ends or portions of which shells are secured to the aforesaid flanges 13^b and the opposite ends of the shells 45 are co-extensive with the ends of the drum. The ends proper of the drum structure consist of flat circular plates each having a central opening. The receiving end plate 14 has an opening so large as to consist of a 50 comparatively narrow flange or rim over and within which all of the materials to be mixed are delivered. The delivery end plate is indicated at 15 and is provided with a central opening of less diameter than that

pertaining to the receiving end. A partition 55 16 is located parallel to the said end plates and at any suitable place between them, preferably substantially mid-way between the receiving end 14 and the central supporting gear member. The partition also has a 60 central circular opening.

A circular series of elevating buckets 17 are secured around the periphery of the receiving end of the drum between the plate 14 and the partition 16. Said buckets may 65 be of any suitable construction and are shown as inclining slightly at their inner ends toward the direction in which the drum is rotated, whereby the materials delivered into the receiving end of the drum will be carried 70 up well above the axis of rotation to be transferred through the opening in the partition 16 into the mixing section of the drum, between the partition and the delivery end 15.

A series of mixing flights 18 are secured 75 within the mixing section of the drum and extend preferably in a spiral and zig-zag relation from the partition to the delivery end thereof. I preferably employ as many of such flights as there are spokes 12. Each 80 flight extends across and is secured to the forward face of its spoke, whereby it is strengthened in its use and transfers the material longitudinally of the drum without interference or obstruction by the spoke. 85 The flights being spirally arranged the forward faces of the spokes are likewise arranged on an incline or are beveled to correspond with the position of the flights. Each flight comprises a main section 18^a 90 extending from the partition 16 to and across its spoke in a continuous spiral direction to a point substantially midway between the gear member and the end 15, at which point it is bent at substantially a right angle forming a section 18^b which extends from the angle spirally in a direction opposite to the direction of the main section 18^a and is secured at its outer end to the end plate 15. By this construction a sort of pocket is 100 formed in each flight between its ends with the effect of providing means for positively moving the material toward the middle portion of the drum in both directions and furthermore to provide means to facilitate the 105 delivery of the mixed material from the drum.

In order to increase the mixing function

of the flights I preferably construct each of them with a section 18^c which is formed from the body of the material constituting the main section 18^a aforesaid, the section 5 18^c lying between the section 18^a and the hub 11 and being bent at an angle from the main section 18^a and extending thence rearwardly to the next succeeding spoke where it is attached and leaving a space between 10 the last mentioned section and the inner surface of the drum. During the operation of the mixing drum the materials to be mixed are first moved by the main sections 18^a between the spokes 12, a portion of such 15 materials continuing along the main sections 18^a until the pockets at the sections 18^b are reached while other portions of the material will fall inwardly toward the axis over the inner edge of the sections 18^a and 20 will be shifted toward the receiving end of the drum again by virtue of the sections 18^c to be again moved forwardly by the succeeding sections 18^a, this process being continued until the material is sufficiently mixed, it 25 being understood that during the mixing operation the sections 18^b will tend to keep the material away from the end plate 15 and toward the intermediate portion of the drum.

30 Any suitable means may be employed to support and rotate the drum upon and around a fixed axis. To this end I have shown a main frame 19 which may be mounted upon any suitable form of truck 35 wheels. An auxiliary frame 20 is secured to the main frame 19 and extends upwardly therefrom opposite the ends of the drum above its axis of rotation. A yoke 21 may 40 be employed to connect the upper ends so as to brace the auxiliary frames 20. A pair of hangers 22 extend downwardly from the upper portions of the frame members 20 and support at their lower ends in any convenient manner a main supporting shaft 23 45 which extends through the hub 11, said shaft constituting the sole support for the drum. The axis of the shaft is fixed or stationary, but the shaft and drum may be rotated around such axis in the bearings 22 50 or if desired the shaft itself may be stationary and the drum rotated upon and around it.

55 By the construction of the receiving end of the drum already described it will be seen that the materials to be mixed are all adapted to be dumped or delivered into the receiving end of the drum near its bottom and below the axis of the drum. By this fact the labor of introducing materials into 60 the drum is much reduced and the bearing portions of the parts are relieved from the wear and rough usage commonly incidental to the materials, especially sand and the like, when they are dumped at a higher 65 point or above the bearings. As shown a

receiving chute 24 is employed to deliver the materials into the buckets 17. The chute 24 is mounted stationarily in any suitable manner upon the main frame 19. The buckets 17 above described will elevate the 70 material thus deposited at the bottom of the drum, and from the buckets such materials will fall upon a transfer chute 25, from which they will glide through the partition 16 into the mixing section to be acted upon 75 by the flights 18 as above set forth. The chute 25 is also stationary and like the chute 24 is free from the drum. As indicated the transfer chute is rigidly connected to the frame section 20 at the receiving end of the 80 structure.

85 As a convenient means for delivering the mixed material from the drum I provide an adjustable delivering spout or chute 26. This is shown as being suspended substantially beneath the shaft 23 and movable circumferentially around the axis thereof. A yoke or bail 27 connects and braces the lateral edges of the chute, maintaining it in trough formation, and the intermediate portion of the bail is pivoted directly upon an extension 23^a of said main shaft on the outside of the bearing bracket 22 adjacent thereto. The main portion therefore of the chute 90 normally hangs suspended by gravity below the shaft, but with the inner end of the chute extending well within the mixing section of the drum the mixed material will fall thereinto from the pockets of the flights and will accordingly be discharged readily from 100 the drum during its continuous rotation.

95 In order to prevent the discharge of the material before the mixing operation is completed the chute 26 is rotated around the axis of the shaft 23 through an angle of substantially 90 degrees as indicated in dotted lines in Fig. 3 where it will be ineffective to receive and discharge the material. A handle 28 is shown attached to the chute for 105 convenient manipulation thereof, and any suitable form of latch 29 may be employed to retain the chute in its non-discharging position, said latch being connected to any convenient portion of the frame, such as the auxiliary member 20. Upon releasing 110 the latch 29 the chute will gravitate to the position indicated in full lines and whereupon the material will be discharged in the manner set forth above. The inner end of the chute 26 may be extended or deflected laterally as at 26^a in order to increase its receiving surface. The extension 26^a in no manner interferes with the mixing operation 115 of the device when the chute is elevated.

120 Any convenient form of motor may be 125 employed to operate the machine. A pinion 30, conveniently journaled upon the frame, is in mesh with the gear teeth 13^a and is adapted to be driven by an engine suitably located at the adjacent end of the frame. 130

This power device being conventional it is thought unnecessary to illustrate or describe the same in detail.

I claim:—

1. In a concrete mixer, a cylindrical drum having a central annular supporting gear member having a hub, spokes, a rim, and flanges extending therefrom toward the ends of the drum, a shaft on which said hub is mounted and constituting the sole support for the drum through said gear member, the curved portion of the drum consisting of a pair of shells attached respectively to said flanges, a head attached to each end of the drum, the head at the receiving end consisting of a narrow circumferential rim, a partition between said receiving end and the gear member and having a central opening for the transfer of material therethrough, a circular series of buckets within the space between said rim and said partition to elevate the material to transfer it as stated, and a series of mixing flights extending spirally between the partition and the delivery end of the drum.

2. In a concrete mixing drum, the combination of a cylindrical shell, means to support the same for rotation about a fixed axis, said supporting means including a gear member having spokes, and a series of flights extending from one end of said shell to the other, each of the flights passing diagonally across and secured to the forward face of a spoke and each flight including an end section formed from the same material as the main section and extending spirally in a different direction therefrom forming a pocket.

3. In a concrete mixer, the combination of a cylindrical shell, means to rotate the shell continuously in a single direction around a

fixed axis, means to deliver materials to be mixed into the said shell, a series of mixing flights secured within said shell, each of the flights being formed of a single blank and extending spirally from one end of the said section to the other and comprising a main section extending spirally in a certain direction, an auxiliary section extending from the end of the main section at an angle and spirally in a different direction, forming a lifting pocket and means tending to move the material toward the middle of the drum and a third section extending rearwardly spirally from the main section at an angle slightly removed from the aforesaid angle between the main and auxiliary sections, and means to discharge the mixed material from the drum.

4. In a concrete mixer, the combination of a frame, a shaft supported upon said frame and extending at one end beyond the frame, a rotatable mixing drum mounted upon said shaft, means to introduce material into one end of the drum, and means at the other end thereof to deliver the mixed material therefrom, said delivering means comprising a chute suspended normally from the aforesaid shaft extension below the axis of the shaft, and means to swing the chute circumferentially around the axis of the shaft to throw it out of delivering position, the inner end of the chute being provided with a lateral projection to increase its receiving capacity, substantially as set forth.

In testimony whereof I have hereunto affixed my signature in the presence of two witnesses.
